UNITED STATES PATENT OFFICE.

LOUIS J. DISSER, SR., OF FERGUSON, MISSOURI.

VENDING MACHINE.

Application filed April 26, 1924, Serial No. 709,306. Renewed August 20, 1925.

To all whom it may concern:

Be it known that I, Louis J. Disser, Sr., a citizen of the United States, and resident of the city of Ferguson, county of St. Louis, and State of Missouri, have invented certain new and useful Improvements in Vending Machines, of which the following is a specification containing a full, clear, and exact description, reference being had to the accompanying drawings, forming a part thereof.

My invention relates to improvements in vending machines and has for its primary object a machine provided with a coin controlled mechanism which upon the insertion of a coin will operate the mechanism and deliver a package of merchandise. The machine being so arranged, however, that by the exercise of skill two packages of merchandise may be obtained for the price of one.

A further object is to construct a vending machine which is coin operated and which will under certain conditions entitle the purchaser to the double amount of goods depending upon the skill of the purchaser, and which is so arranged as to preclude any possibility of manipulating the machine so as to cause it to pay double the amount.

In the drawings:

Fig. 1 is a front elevation of my device;

Fig. 2 is a side elevation of the same viewed from the operating side;

Fig. 3 is a rear view with the door open and parts broken away;

Fig. 4 is a vertical section taken on the line 4—4 of Fig. 3;

Fig. 5 is a horizontal section taken on the line 5—5 of Fig. 1 with parts thereof broken away;

Fig. 6 is a vertical section taken on the line 6—6 of Fig. 1;

Fig. 7 is a vertical section taken on the line 7—7 of Fig. 3;

Fig. 8 is an enlarged perspective view of one of the delivery fingers;

Fig. 9 is a vertical longitudinal section of the coin receptacle; and

Fig. 10 is a diagrammatic view showing the position of the shooting spring, coin receptacle, and the lower portion of the plate in which the coin path is formed.

In the construction of my device I employ

a cabinet or casing having a base 11, a top 12, side members 13 and 14, and a rear door 15. The sides 13 and 14 are L-shaped in plan so that the lower end thereof is wider than the remaining portion. This wider portion is closed by means of a front 16 and a top 17. The side members 13 and 14 as well as the top are provided with grooves in which a sheet of glass 18 is fitted, this glass forming the remainder of the front of the device.

Secured within the casing is a partition 19 which is supported within the casing by means of brackets 20 and 21. Secured to the outer face of the wall 19 is a plate 22 which may be either of metal, wood or similar material. The plate 22 has its exposed surface resting against the glass 18, and in this surface is formed a coin path in the shape of an inverted U having a coin receiving passage 23 and a coin discharge passage 24 which are joined together at their upper ends by the curved passage 25. The passages 23 and 24 extend vertically and their lower ends extend to the lower edge of the plate 22. Intermediate the passages 23 and 24 is a vertical passage 26 which is connected to the passage 25 by an inclined passage way 27. The passage way 27 opens into the passage way 25 beyond the vertical center of the passage way 25 and toward the side of the passage 24, the purpose of this will be explained in detail later.

It will be noted that the passage 26 does not extend to the end of the plate but forms a pocket so that any coin lodging in the passage 26 will be retained therein and visible through the glass front 18.

The passages 24 and 26 are connected together by means of a by-pass 28, this passage permits the ready shaking of the coin from the pocket formed by the passage 26 into the discharge passage 24 without the necessity of tilting the machine to any great extent, this however will be described in detail later.

Formed in the plate 22 and connecting with the receiving passage 23 is an inclined passage 29, this passage inclines upwardly and terminates against the side wall 13 and in alignment with a slot 30 cut therethrough. This slot is of sufficient size to permit the insertion of a coin of a predetermined diameter.

ter. Secured to the side 13 and adjacent the slot 30 is a coin chute 31 which has its bottom inclined so that when a coin is placed therein it will readily roll down through the passage 29 and into the passage 23.

Secured to the bottom 11 is a substantially U-shaped spring member 32, its ends 33 being secured to the bottom 11, while the end 34 projects through a slot 35 formed in the front 16. The upward movement of the lever 32, which will hereafter be termed the shooting lever, is limited by means of a bumper 36 which is secured to the top 17 and is of any resilient material. It will be noted from Figs. 5 and 10 that the shooting spring or lever 32 is located directly beneath the passage 23 so that when a coin enters the passage 23 it will rest on the spring, as shown by light dotted lines in Fig. 10, and on the depression of this spring will follow the same downward as indicated by the heavy dotted lines in Fig. 10. The shooting lever or spring however, has its downward movement so limited so there is no possibility of the coin dropping entirely out of the passage 23.

Pivottally carried by the plate 22 is a gate 37, this gate is located above the passage 29 and is free to swing outward, as indicated by the dotted arc in Fig. 1, and close off the passage 23 from the passage 25. This is one of the safe guards against the manipulation of the machine which will be explained in detail later. Located in the passage 25 and extending through the plate 22 is an opening 39 which registers with an opening 40 formed in the partition of back 19, and extending into these openings is the leg 41 of an L-shaped wire 42. The opposite end of the wire being hooked through an eye 43 carried by the partition 19. The L-shaped wire is so hung as to swing freely in the eye 43. Secured to the partition 19 is a bracket 44 in which is pivotally supported a wire 45, its end 46 passing to the rear of and around the wire 42, while the end 47 extends downwardly and is provided with a weight 48. The wire 42 and the wire 45 are also intended to prevent manipulation of the machine, as will be explained in detail later.

The sides 13 and 14 are provided with bearing plates 49 which are arranged opposite each other and which provide bearing for the shaft 50, this shaft is so located as to pass entirely through the machine and be centered below the passages 23 and 24. The shaft 50 projects through the side 13 and is provided with a crank 51 and a handle 52. The movement of the crank and handle is limited by means of pins 53 and 54, the purpose of which will be explained in detail later. The handle and crank are normally held in the position illustrated in Fig. 2 by means of a spring 55.

Secured to the shaft 50 and directly below

the passage 24 is a coin receptacle 56 which is provided with a pocket 57, this pocket is of such a depth as to permit a portion of the coin, as illustrated in Figs. 9 and 10, to project beyond the upper surface. This is for the purpose of permitting the upper portion of the coin to engage with fingers 58 which are carried by the delivery fingers 59, these fingers in turn being secured to a roller or similar support 60. This roller is loosely mounted on the shaft 50 so as not to turn therewith unless the fingers 58 are contacted with by a coin and in order to prevent accidental rotation a spring 61, which presses against the roller 60, is employed, the lower end of this spring being secured to the base 11. The delivery fingers 59 are preferably four in number and are secured to the roller 60 in any well known manner. Each of the delivery fingers is provided with integral upwardly extending projections 62, these projections are adapted to engage with a package of merchandise and move it toward the delivery point.

Located between the wall 14 and the vertical edge of the partition wall 19 is a magazine consisting of two vertical L-shaped strips 63, these strips are located at the rear of the magazine, the front wall formed by the glass plate 18.

Formed integral with the members 63 are horizontal strips 64 which form the bottom of the magazine and which connect with a delivery plate 65, this plate is provided with slots 66 through which the fingers or projections 62 pass. The delivery plate 65 is so shaped as to present an inclined surface so that as soon as a package of merchandise is carried off of the bottom 64, gravity will cause it to descend over the plate 65 and out through the delivery opening 67 formed in the front 16. The magazine is closed by means of a removable plate 68, the lower end of which is held in position by means of springs 69, while the upper end is held in position by means of a swivel latch 70. In this way the magazine may be completely closed except on its bottom.

The door 15 is provided with hinges 71 and with a lock 72 so that unauthorized access to the interior of the housing cannot be readily had, as the interior of the housing not only contains the merchandise magazine but also acts as a receptacle for the coins after the merchandise has been delivered.

The removable plate 68 is also provided with a knob 73 by means of which it can be readily lifted out of position for charging the magazine.

In order to secure the coin receptacle 56 to the shaft 50, the shaft is preferably provided with a flattened portion 74 against which the end of a screw 75 is seated. This method of securing the coin receptacle prevents any possibility of its turning on the

shaft, which turning would result in the device not working properly as there would be a possibility, should the receptacle turn, of the coin dropping straight through into the casing and preventing the machine from delivering the merchandise.

The operation of my device is as follows:—

After the magazine has been properly loaded the device is placed on the counter and is ready for operation. The customer inserts a coin of the proper size or denomination into the coin chute 31 and permits it to pass through the slot 30 and then down into the passage 23 where it contacts with the shooting lever 32. The end 34 of this lever is then depressed, as indicated in Fig. 4, and released suddenly allowing the lever to snap up. This shoots the coin upward in the passage 23 until it strikes the curved passage 25 around which it passes and down through the passage 24. After leaving this passage it lodges in the pocket 57 of the coin receptacle in such a manner that its upper edge projects beyond the top edge of the receptacle and in line with one of the fingers 58. The handle 52 is then pulled forward until the crank contacts with the pin 54, this movement rotates the sleeve 60 causing the fingers 62 to rotate and contact with a package of merchandise which is carried forward and slides down the delivery plate 65 and is removed through the opening 67. During this operation the spring 61 rides over the bars of the delivery finger 59 which projects beyond the face of the sleeve or roller 60 (see Fig. 6). The purpose of having these fingers projecting beyond the face, it that when the spring 61 rides over one of these bars its tendency, due to the curved contacting end, is to force the bar forward. This disengages the finger or projection 58 from contact with the coin and allows the coin to slide out of the pocket and lodge in the casing from where it is removed through the door 15.

The object of the person purchasing merchandise from this machine is to shoot the coin just hard enough so that it will pass by the center of the curved passage 25. If this is done, gravity will allow the coin to enter the slot or passage 27 and drop into the pocket 26. The vendor's attention is then drawn to the machine, and upon seeing the coin in the pocket, the purchaser is given an extra piece of merchandise. It is preferred to leave the first coin in the pocket 26, as indicated by dotted lines in Fig. 1, in this instance the purchaser is given two packages of merchandise, should the following purchaser also cause his coin to enter the pocket 26 it lodges on the coin already therein, and upon the vendor's attention being called thereto, presents the purchaser with an article of merchandise. The casing is then tilted so that the second coin will enter

the passage 24 through the by-pass 28, after which the machine is manipulated in the usual manner.

It is of course essential in order to get two articles of merchandise to shoot the coin upward just hard enough to make it pass by the center of the curved passage 25 so that gravity will permit it to enter the passage 27. If the coin is shot too hard centrifugal force of the coin, while passing through the curved passage, will hold it against the outer or upper edge thereof and direct it into the slot 24, in this instance the purchaser only receives the actual amount of merchandise paid for.

Should an attempt be made to manipulate the machine by tilting it toward the handle 52 so that its passage through the curved portion 25 will be retarded, the gate 37 swings outward and blocks the passage 23 thus preventing the coin from passing upward into the passage 25. If the device is tilted forward with the same purpose in view, the wire 42 being freely suspended from the eyelet 43 moves inward, the portion 41 projecting through the openings 39 and 40 and into the passage 25 thus preventing the coin from passing over the center of the curved passage way. And if the machine is tilted backward the weight 48 swings out forcing the hook 46 inward and thus causing the portion 41 of the wire 42 to project into the passage. There would be no incentive to tilting the machine in the direction opposite from the handle because in that instance there would be no possible chance of the coin entering the passage 27, so that it will be readily understood that my device cannot be fraudulently manipulated either by tilting the machine forward or backward or toward the side on which the operating handle is located because in either instance the coin is prevented from passing the center of the curved passage 25 and drops back into the passage 23 where it must be replayed.

My device is arranged for coins of a pre-determined size depending on the value of the merchandise to be dispensed, the size of the slot 30 preventing a larger coin than the predetermined size from being inserted. While the pocket in the coin receptacle is of such a size that if a smaller coin than that intended for the machine is used, it will not project far enough out of the receptacle to operate the delivery fingers so that on pulling the handle forward the coin will be discharged into the machine without dispensing any merchandise whatever.

Having fully described my invention, what I claim is:—

1. A vending machine comprising a cabinet, a plate having visible spaced apart receiving and discharging coin passages, a curved passage connecting said passages at

their upper ends, a pocket formed in said plate between the receiving and discharging passages and communicating with the curved passage to the side of its center adjacent the discharge passage, means for projecting a coin through certain of said passages, a coin receptacle located beneath the discharge passage, and means for rocking said coin receptacle for discharging the coin therefrom.

2. A vending machine comprising a cabinet, a plate having visible spaced apart receiving and discharging coin passages, a curved passage connecting said passages at their upper ends, a pocket formed in said plate between the receiving and discharging passages and communicating with the curved passage to the side of its center adjacent the discharge passage, means for projecting a coin through certain of said passages, a passage between said pocket and the discharging passage for permitting a coin to be removed from said pocket, means located in the receiving passage for obstructing the passage of a coin therethrough when the cabinet is tilted sidewise, a coin receptacle located beneath the discharge passage, and means for rocking said coin receptacle whereby said coin is discharged therefrom.

3. A vending machine comprising a cabinet, a plate having visible spaced apart receiving and discharging coin passages, a curved passage connecting said passages at their upper ends, a pocket formed in said plate between the receiving and discharging passages and communicating with the curved passage to the side of its center adjacent the discharge passage, means for projecting a coin through certain of said passages, a coin receptacle located beneath the discharge passage, means for discharging the coin from said coin receptacle, and means adapted to extend into the curved passage at its center for preventing the passage of a coin when the cabinet is tilted backward or forward.

4. A vending machine comprising a cabinet, a vertical plate having visible spaced apart receiving and discharging coin passages, a curved passage connecting said passages at their upper ends, a pocket formed in said plate between the receiving and discharging passages and communicating with the curved passage to the side of its center adjacent the discharge passage, a spring lever located beneath the receiving passage for projecting a coin through certain of said passages, means located in the receiving passage for obstructing the passage of a coin therethrough when the cabinet is tilted sideways, a coin receptacle located beneath the

discharge passage, and means adapted to extend into the curved passage at its center for preventing the passage of a coin when the cabinet is tilted backward or forward.

5. A vending machine comprising in combination with a cabinet having a rear door and a sheet of glass in its front, a plate located within the cabinet against said glass, an inverted U shaped coin path having a receiving passage and a discharging passage formed in one face of said plate, a shooting lever located below and in alinement with the receiving passage, a coin receptacle located beneath the discharge passage, means for rocking said receptacle, a coin pocket formed in said plate between the receiving and discharging passages and communicating with the coin path, and means for permitting the insertion of a coin into the receiving passage.

6. A vending machine comprising a cabinet having a rear door and a sheet of glass in its front, a plate located within the cabinet against said glass sheet, an inverted U shaped coin path having a receiving passage and a discharging passage formed in one face of said plate, a spring shooting lever located below and in alinement with the receiving passage, a coin receptacle located beneath the discharge passage, means for rocking said receptacle, a coin pocket formed in said plate between the receiving and discharging passages and communicating with the coin path, means for permitting the insertion of a coin into the receiving passage, and means for preventing the entrance of a coin into the discharge passage when the cabinet is tilted.

7. A vending machine comprising a cabinet having a glass plate in its front wall, a plate having a visible coin passage located in said cabinet and against said glass, a shooting lever projecting from said cabinet for projecting a coin through said passage, a coin receptacle adapted to receive said coin after the same has been projected through the passage, a pocket formed in said plate and communicating with the coin passage, for permitting the lodging of a coin therein, means located at one side of the coin passage and above the shooting lever for blocking the passage of the coin when the cabinet is tilted sidewise, and means adapted to be projected into the coin passage when the cabinet is tilted forward or backward for blocking the passage of a coin therethrough.

In testimony whereof, I have signed my name to this specification.

LOUIS J. DISSER, Sr.
